UNITED STATES PATENT OFFICE.

WILLIAM CRAINE, OF BROOKFIELD, NEW YORK.

WOODWORKING-MACHINE.

1,114,968.

Specification of Letters Patent. Patented Oct. 27, 1914.

Application filed April 3, 1914. Serial No. 829,363.

To all whom it may concern:

Be it known that I, WILLIAM CRAINE, a citizen of the United States, residing at Brookfield, in the county of Madison and State of New York, have invented a new and useful Woodworking-Machine, of which the following is a specification.

This invention relates to wood working machines and more particularly to machines for shaping the ends of boards, scantling, poles and other timbers, for use in making splice or scarf joints.

Another object is to provide a machine of this character utilizing a novel arrangement of saws and burs for producing shoulders or abutments and tongues at the ends of the timbers whereby the said timbers when brought together, will conceal the interfitting tongues, thus rendering the joint particularly useful in connection with flooring.

A further object is to provide gangs of burs so mounted as to be readily moved into and out of active positions by the operator.

25 A further object is to provide means for limiting the movement of the stock relative to the burs so that successive pieces of stock will be of the same shape and proportions at their ends.

30 With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

40 In the accompanying drawings the preferred form of the invention has been shown.

In said drawings:—Figure 1 is a plan view of the machine, the protecting hoods being removed. Fig. 2 is a section on line A—B Fig. 1. Fig. 3 is a section on line C—D Fig. 1. Fig. 4 is a plan view of a portion of one of the feed tables and of the gage used in connection therewith. Fig. 5 is a perspective view of two members of a joint such as may be produced by means of the machine herein described and as is used principally in connection with flooring. Fig. 6 is a section through the meeting members of the joint. Fig. 7 is a perspective view of the two members of a joint such as employed primarily in splicing. Fig. 8 is a

side elevation of said members interfitting. Fig. 9 is a section on line E—F Fig. 1. Figs. 10, 11 and 12 are detail views of the parts of the stop. Fig. 13 is a perspective view of one end portion of the feed table or slide which cooperates with the stop. Fig. 14 is a perspective view of a portion of the structure and showing the guide arm depending from one of the hinged frames.

Referring to the figures by characters of reference 1 designates a supporting structure on which is arranged a table 2 projecting forwardly beyond the supporting structure and having a downwardly turned flange 3 along its front edge. Formed in this table near one side of the machine is a transversely extending slot 4 while located in the table near the opposite side thereof is a group of parallel longitudinal slots 5. 60 Mounted on the table between the slots 5 and the adjacent side of the table is a gage including a base plate 6 having an upstanding flange 7, this flange extending longitudinally of the table and parallel with the slots 5. 70 The base plate 6 has a depending flange 8 at its front end engaging the front edge of the table 2 while a transverse slot 9 is formed in the base plate and receives a clamping bolt 10 upstanding from the table. Thus it will 75 be seen that the gage can be adjusted transversely of the table.

A feed table or slide 11 is mounted on the table 2 and is provided, along one side, with an upstanding flange 12 which is bent downwardly so as to straddle the flange 7, as shown in Fig. 9. Thus the slide or feed table 11 is properly guided during its movement longitudinally of the machine. That end of the feed table 11 nearest the slots 5 80 is provided with parallel fingers 13 designed to project between the slots 5.

85 Mounted on the table 2 and back of the slots 5 is an angular bracket 14 having a slot 15 in its base adapted to receive a clamping bolt 16 whereby the bracket can be held against movement relative to the table 2. By providing the slot 15, however, the said bracket can be adjusted longitudinally of the table. The upstanding portion of 90 bracket 14 is formed with a longitudinal slot 17 for the reception of a clamping bolt 18 which extends into a slot 19 formed longitudinally within the upstanding end 20 of the bottom plate 21 of a stop. This bottom 95 plate has fingers 22 at its free end adapted to extend between the slots 5 and into the

path of the fingers 13. A longitudinal slot 23 is formed in the bottom plate 21 and is designed to receive a clamping bolt 24 which extends through a slot 25 in the base 26 of a stop 27. This stop extends transversely of the plate 21. It will be apparent that by mounting the stop in the manner set forth, the bottom plate 21 can be adjusted upwardly and downwardly by loosening the bolt 18, the stop 27 can be adjusted toward or from the fingers 22 by loosening the bolt 24, and the entire structure can be shifted bodily toward or from the slots 5 by loosening the bolt 16. As shown in Fig. 2, the free ends of the fingers 13 on the slide or feed table 18 are upturned so as to ride onto the fingers 22 and come against the stop 27. Furthermore these fingers have their free ends folded and provided with upwardly extending ears 28 constituting abutments for stock as hereinafter set forth.

Extending transversely within the rear end portion of the supporting structure 1 at the back end thereof is a shaft 29 on which a frame 30 is mounted to swing. The free end portion of this frame carries a transverse shaft 31 to which is secured a series of burs or cutters 32 designed to move upwardly into the respective slots 5. A pulley 33 is secured to the shaft 31 and receives motion, through an endless belt 34, from a pulley 35 secured to the shaft 29. An arched adjusting rod 36 extends under the frame 30 and is journaled within the supporting structure 1 and this rod is provided with an arm 37 whereby it can be actuated readily for the purpose of swinging the frame 30 upwardly or downwardly. When the frame is swung upwardly, the cutting disks or burs 32 will move into and through the slots 5 and against the stock which may be supported thereabove whereas, when the frame 30 is moved downwardly, the cutting elements 32 will be withdrawn from the slots 5.

A transverse shaft 38 is journaled within the upper portion of the supporting structure and above the rear end of the table 2 and this shaft supports a swinging frame 39 the front or free end of which carries a transverse shaft 40 on which is arranged a series of cutting disks or burs 41. These cutting disks or burs are located directly above the fingers 13 or, in other words, are staggered relative to the cutting elements 32. A pulley 42 rotates with the cutting elements 41 and receives motion, through an endless belt 43 or the like, from the pulley 35 hereinbefore referred to, there being suitably arranged guide pulleys 44 within the rear portion of the frame 39 as shown in Fig. 2. This upper frame has an arcuate guide rod 45 depending loosely therefrom and engaged by an eye bolt 46 which, when tightened, as by means of a nut 47, will be

caused to bind upon the rod and thus lock the frame 39 at any angle to which it may be adjusted. As shown particularly in Fig. 2, a hood 48 may be hingedly connected to the frame 39, this hood being provided with angular side wings 49 for supporting the hood in position over the cutting elements 41. When the hood is not to be used it can be swung back as shown by dotted lines in said Fig. 2.

When it is desired to form one end of a timber with oppositely pitched tongues disposed in staggered relation as shown, for example, in Fig. 7, the burs 32 and 41 are adjusted toward each other and the timber to be cut is placed on the slide or feed table 11 so that it will abut against the upstanding ears 28. The said timber is then fed forward until the fingers 13 come against the stop 27. During this forward movement of the timber, it is brought between and against the rapidly rotating cutting elements 32 and 41 and consequently, a product such as shown in Fig. 7 will thus be produced. Obviously the same form of scarf or splice joint can be produced in other forms of lumber. In the form shown in Fig. 7, two pole sections have been shown with ends shaped in the manner hereinbefore described. It will be understood that as soon as the end of the timber has been slotted or tongued in the manner set forth, the cutting elements 32 can be lowered by rotating the arched rod or bar 36 and, by loosening the nut 47, the guide rods 45 will be loosened and the frame 39 can then be swung upwardly. Thus the cutting elements 41 will be lifted out of engagement with the stock.

Slidably mounted on the table 2 at one side of the machine is a feed table or slide 50 having an upstanding longitudinal flange 51 along one side thereof while depending from the front end of this feed table or slide is a downwardly and upwardly curved flange 52 adapted to engage the flange 3, thus to hold the table or slide 51 against longitudinal displacement while permitting said slide or table 50 to be shifted transversely of the table 2.

A bracket 53 is arranged within the lower portion of the supporting structure 1 and mounted to swing on this bracket is a frame 54 carrying a longitudinal shaft 55. A saw 56 is connected to the upper end of the shaft and a pulley 57 is carried by the shaft and is adapted to receive motion through a belt 58 from a pulley 59 secured to the shaft 29 hereinbefore referred to. Saw 56 is adapted to project upwardly through the slot 4 hereinbefore referred to and back of the slide or table 50.

The frame 55 has an arcuate arm 60 extending upwardly and forwardly therefrom and adapted to be engaged by an eye bolt

61 similar to the bolt 46 hereinbefore referred to, a nut 62 being provided for tightening said bolt upon the arm 60, thus to hold the frame 55 at any angle to which it may be adjusted. Any suitable tightener 63 may be employed for holding the belt 58 taut after the frame 55 has been adjusted angularly.

The shaft 38 constitutes the fulcrum for 10 a frame 64 which overhangs the rear portion of the table 2 and carries a shaft 65 having a saw 66 at its front end and movable to position above the slot 4. This shaft 65 has a pulley 67 designed to receive motion, through a belt 68, from the pulley 59.

An arcuate rod 69 extends downwardly and rearwardly from the frame 64 and is adapted to be engaged by an eye bolt 70 similar to the bolts 46 and 61 hereinbefore 20 referred to, this bolt 70 being engaged by a nut 71 whereby the bolt 70 can be tightened on the rod 69 and the frame 64 thus held in any position to which it may be adjusted about the shaft 38.

25 In Fig. 5 sections of flooring have been shown. It will be noted that each of these sections has a shoulder 72 extending transversely thereof and that the tongues 73 of the lap joints are formed below these shoulders. Thus when the two sections are brought together the tongues 73 will be concealed and the only portion of the joint disclosed will be the meeting shoulders 72. The machine which has been described is particularly designed for producing an article such as shown in Fig. 5. In the manufacture of such an article, the timber is placed on the table or slide 50 and with one end projecting past the saws 56 and 66. After 40 the saws have been adjusted toward each other as shown in Fig. 3, the table or slide 50 is shifted transversely of the table 2, thus bringing the end portion of the timber against the saws. The upper saw 66 will 45 produce the shoulder 72 while the lower saw 56 will cut the bevel at the end of the timber and which forms the free ends of the tongues 73. After the end of the timber has thus been shaped, it is lifted from the 50 slide or table 50 and placed on the slide 18. The cutting elements 41 are lifted out of active position while the cutting elements 32 are projected upwardly through the slots 5. The slide 18 is then advanced toward 55 the cutting elements, thus bringing the lower portion of the timber into engagement with said cutting elements so that the tongues 73 will thus be produced. The cutting elements 41 are only employed where 60 a double lap such as shown for example in Fig. 7, is to be produced.

What is claimed is:—

1. A wood working machine including a slotted table, a feed slide having fingers 65 movable between the slots, an adjustable stop

in the path of the fingers for limiting the sliding movement of the fingers, and a series of cutting elements shiftable into and out of the slots in the table for engaging the stock supported by the fingers.

70

2. A wood working machine including a slotted table, a stock supporting slide having fingers movable between the slots, frames above and below the table and mounted to swing upwardly and downwardly relative thereto, said frames being independently adjustable, a series of cutting elements carried by each frame, and means for actuating said elements, the said elements being adapted to engage the stock between and within the slots respectively.

75

3. A wood working machine including a slotted table, a stock supporting slide having fingers movable between the slots, an adjustable stop for limiting the movement of the slide and stock, a frame mounted to swing below the table, a series of revoluble cutting elements carried thereby, means for driving said cutting elements, and means for swinging the frame to move the cutting elements into and out of the slots.

80

4. A wood working machine including a slotted table, a stock supporting slide having fingers movable between the slots, adjustable means for limiting the movement of the slide, a pivotally supported frame mounted to swing toward and from the table, a series of revoluble cutting elements carried by the frame, means for actuating said elements, and means for shifting the frame toward and from the stock carried by the slide.

85

5. In a wood working machine the combination with a table, said table having slots therein, and a stock supporting slide on the table and having fingers movable between the slots, of a bracket adjustably mounted on the table, a bottom plate adjustably connected to the bracket, said bottom plate being inclined and having fingers extending between the slots and in the path of the fingers of the slide, a stop adjustably mounted on said bottom plate and in the path of the fingers on the slide, and cutting elements insertible into the slots for engaging stock mounted on the slide.

90

6. In a wood working machine the combination with a table, said table having slots therein, and a stock supporting slide on the table and having fingers movable between the slots, of a bracket adjustably mounted on the table, a bottom plate adjustably connected to the bracket, said bottom plate being inclined and having fingers extending between the slots and in the path of the fingers on the slide, a stop adjustably mounted on said bottom plate and in the path of the fingers on the slide, cutting elements insertible into the slots for engaging stock mounted on the slide, and upstanding stop devices upon the fingers on

the slide and constituting abutments for the stock.

7. In a wood working machine the combination with angularly disposed upper and lower cutting elements coöperating to produce a shoulder and bevel within stock supplied thereto, of a supporting table, a feed table slidably mounted thereon, and movable transversely thereof for directing stock against the cutting elements, superposed series of cutting elements coöperating to form tongues in staggered relation, a feed

slide for receiving the shouldered and beveled stock and directing it against said last named cutting elements, and means for 15 limiting the movement of said feed slide.

In testimony that I claim the foregoing as my own, I have hereto affixed my signature in the presence of two witnesses.

WILLIAM CRAINE.
